FLANGE BEAMS OF WOOD

Karl Hilding Brosenius, Stockholm, Sweden

Application July 23, 1947, Serial No. 762,870
In Sweden April 19, 1941Section 1, Public Law 690, August 8, 1946
Patent expires April 19, 1961

7 Claims. (Cl. 20—0.5)

1

Flange beams of wood, the webs of which comprise two or more layers of separate boards, crossing each other diagonally, have lately been frequently used for building purposes. When constructing the skeleton for buildings the problem often arises how to join such beams in an angle giving this joint a both attractive appearance and sufficient strength. In order that the combined beam construction may then transmit momenta and shearing forces as well as perpendicular forces respectively through the angle to the same amount as in an unbroken beam, it has hitherto been considered necessary to make such joint by means of nailed-on joint-pieces or knees, most frequently by using special bolted iron fittings of plane iron or any other forging or by means of wood-constructions bolted together. Such joints as hitherto known generally make the construction voluminous and ugly, and besides it has not been possible heretofore to make such joints otherwise than with a fairly limited number of power transmissions through the joint.

The main object of the present invention is to avoid these drawbacks. Another object is to provide a construction which is simple to manufacture and has a smooth appearance and great strength.

In order to better illustrate the present invention two embodiments thereof are shown in the accompanying drawing.

Fig. 1 shows an elevation of one embodiment of a frame construction composed of the beam portions, the two joints between the three beams being constructed according to the invention;

Fig. 2 shows on a larger scale an elevation of one of said joints with the two beam portions spaced apart;

Fig. 3 shows on a still larger scale a detail of the joint according to Fig. 2 viewed in elevation and with the two beam portions in interconnected position;

Fig. 4 is a vertical section on the line a—a in Fig. 3; and

Fig. 5 is a horizontal section on the line b—b in Fig. 3.

The embodiment according to the drawing shows two beams A and B (termed hereinafter the first beam and the second beam, respectively) to be joined at a corner or an angle H. Each beam consists of a web L having at least two layers of boards crossing each other diagonally (see Fig. 3) and flanges F₁ and F₂ of wooden bars attached to the longitudinal edges of said web. The crossing boards of the web L are indicated in Fig. 3 only. The first flanges F₁ of the first

2

beam A define with the second flanges F₂ of the second beam B a quadrangular corner portion to which are superimposed the boards of the web layers extending substantially parallel to the diagonals of the quadrangular corner portion, respectively. At the corner H there occur considerable flange forces, partly in the vertical section a—a (Fig. 3) through the horizontal beam portion A, partly in the horizontal section b—b through the vertical beam portion B. In order to enable the construction of a corner joint resistant to bending it is necessary to transform the vertical flange forces into horizontal forces or vice versa. This is made possible in a very economic and convenient manner by applying a closed bar-system at the place of the joint H, this system comprising (1) the web boards of one beam A crossing each other diagonally and statically acting as rods and (2) wood strips, arranged around the joint so as to form a closed quadrangle cdef. The strips constitute the flanges F₁ of the beam A and the flanges F₂ of the beam B together with strengthening laths U, V between the flange portions cd, fe.

The flanges or laths F₁, F₂ are joined together and attached to the web boards by so close a nailing (if desired in combination with gluing and/or bolts) that the nails are able to transmit the forces in the corner construction from the flanges at the one beam to the other one. The vertical forces in the strips U and V are transformed into horizontal forces in the flange portions dc and ef by the resolution of components in the boards of the two diagonal panel layers so that the stress or force components are directed in direction of, and taken up by, a board parallelogram having a vertex in the stressed point and being composed of one pair of boards of each of the layers, said nails defining a plurality of quadrilaterals inscribed to the quadrilateral defined by the first flanges and the second flanges. Fig. 3 illustrates how for instance part of the flange force in the flange fc through a nail S is resolved into two oblique components, which are transmitted to the horizontal flanges. In the same way the forces are divided in the other flanges. By constructing the corner in this manner very great momenta may be transmitted in a very simple way without any other connecting elements but nails and if desired glue. Furthermore the corner will be very attractive in its appearance as no supplementary knee reinforcements are used. This method may be applied also in those cases when the corner is not right-angled but forms an acute or obtuse angle.

The vertical beam B may preferably be provided with a horizontal bar M impinging on the flange portion *fe*. In order to transmit horizontal shearing forces in the contacting area between the bar M and the flange portion *fe* an oak block P or the like may be inserted, or the parts M and *fe* may be joined by means of cross-diagonal panel sheets nailed onto both sides.

What I claim is:

1. A beam structure comprising two angularly arranged flanged beams having flanges along the longitudinal edges thereof; flanged end portions at the ends of said beams to be joined at a corner, said flanged end portions of one beam overlapping said flanged end portions of the other beam and forming with the same a quadrangular corner portion; two layers of elongated boards superimposed upon said quadrangular corner portion and constituting a web covering said quadrangular corner portion, the boards of one of said layers extending substantially parallel to one diagonal of said quadrangular corner portion and the boards of the other of said layers extending substantially parallel to the other diagonal of said quadrangular corner portion; and a plurality of connecting means firmly connecting said superimposed layers of elongated boards to each other and to said flanged end portions at a substantial number of points spaced in longitudinal direction of said flanged end portions all along the same whereby components of stress created at any of said spaced points are directed in direction of, and taken up, by a board parallelogram having a vertex in the stressed point and being composed of one pair of boards of each of said layers.

2. A beam structure comprising two angularly arranged flanged beams having flanges along the longitudinal edges thereof; flanged end portions at the ends of said beams to be joined at a corner, said flanged end portions of one beam overlapping said flanged end portions of the other beam and forming with the same a quadrangular corner portion; two layers of elongated boards superimposed upon said quadrangular corner portion and being continuous with the web of one of said beams, the boards of one of said layers extending substantially parallel to one diagonal of said quadrangular corner portion and the boards of the other of said layers extending substantially parallel to the other diagonal of said quadrangular corner portion; and a plurality of nails firmly connecting said superimposed layers of boards to each other and to said flanged end portions at a substantial number of points spaced in longitudinal direction of said flanged end portions all along the same whereby components of stress created at any of said spaced points are directed in direction of, and taken up, by a board parallelogram having a vertex in the stressed point and being composed of one pair of boards of each of said layers.

3. A beam structure comprising two angularly arranged flanged beams having flanges along the longitudinal edges thereof; flanged end portions at the ends of said beams to be joined at a corner, said flanged end portions of one beam overlapping said flanged end portions of the other beam and forming with the same a quadrangular corner portion; a pair of strengthening strips being arranged between said flanged end portions of one of the beams and parallel to said flanged end portions of the other of the beams; two layers of elongated boards superimposed upon said quadrangular corner portion and constituting a web covering said quadrangular corner portion, the boards of one of said layers extending substantially parallel to one diagonal of said quadrangular corner portion and the boards of the other of said layers extending substantially parallel to the other diagonal of said quadrangular corner portion; and a plurality of connecting means firmly connecting said superimposed layers of elongated boards to each other and to said flanged end portions at a substantial number of points spaced in longitudinal direction of said flanged end portions all along the same whereby components of stress created at any of said spaced points are directed in direction of, and taken up, by a board parallelogram having a vertex in the stressed point and being composed of one pair of boards of each of said layers.

web covering said quadrangular corner portion, the boards of one of said layers extending substantially parallel to one diagonal of said quadrangular corner portion and the boards of the other of said layers extending substantially parallel to the other diagonal of said quadrangular corner portion; and a plurality of connecting means firmly connecting said superimposed layers of elongated boards to each other and to said flanged end portions and said strips at a substantial number of points spaced in longitudinal direction of said flanged end portions all along the same whereby components of stress created at any of said spaced points are directed in direction of, and taken up, by a board parallelogram having a vertex in the stressed point and being composed of one pair of boards of each of said layers.

4. A beam structure comprising two angularly arranged flanged beams having flanges along the longitudinal edges thereof; flanged end portions at the ends of said beams to be joined at a corner, said flanged end portions of one beam overlapping said flanged end portions of the other beam and forming with the same a quadrangular corner portion; a pair of strengthening strips being arranged between said flanged end portions of one of the beams and parallel to said flanged end portions of the other of the beams; two layers of elongated boards superimposed upon said quadrangular corner portion and constituting a web covering said quadrangular corner portion and being continuous with the web of one of said beams, the boards of one of said layers extending substantially parallel to one diagonal of said quadrangular corner portion and the boards of the other of said layers extending substantially parallel to the other diagonal of said quadrangular corner portion; and a plurality of nails firmly connecting said superimposed layers of elongated boards to each other and to said flanged end portions and said strips at a substantial number of points spaced in longitudinal direction of said flanged end portions all along the same whereby components of stress created at any of said spaced points are directed in direction of, and taken up, by a board parallelogram having a vertex in the stressed point and being composed of one pair of boards of each of said layers.

5. A beam structure comprising two angularly arranged flanged beams having flanges along the longitudinal edges thereof, flanged end portions at the ends of said beams to be joined at a corner, said flanged end portions of one beam overlapping said flanged end portions of the other beam and forming with the same a quadrangular corner portion, said flanged end portions at the ends of one of the beams being substantially parallel and horizontal, said flanged end portions at the ends of the other of the beams being substantially upright; two layers of elongated boards superimposed upon said quadrangular corner portion and constituting a web covering said quadrangular corner portion, the boards of one of said layers extending substantially parallel to one diagonal of said quadrangular corner portion and the boards of the other of said layers extending substantially parallel to the other diagonal of said quadrangular corner portion; and a plurality of connecting means firmly connecting said superimposed layers of elongated boards to each other and to said flanged end portions at a substantial number of points spaced in longitudinal direction of said flanged end portions all along the same whereby components of stress created at any of said spaced points are directed in direction of, and taken up, by a board parallelogram having a vertex in the stressed point and being composed of one pair of boards of each of said layers.

said spaced points are directed in direction of, and taken up, by a board parallelogram having a vertex in the stressed point and being composed of one pair of boards of each of said layers.

6. A beam structure comprising two angularly arranged flanged beams having flanges along the longitudinal edges thereof, flanged end portions at the ends of said beams to be joined at a corner, said flanged end portions of one beam overlapping said flanged end portions of the other beam and forming with the same a quadrangular corner portion, said flanged end portions at the ends of one of the beams being substantially parallel and horizontal, said flanged end portions at the ends of the other of the beams being substantially upright; a pair of strengthening laths being arranged between said flanged end portions of one of the beams and parallel to said flanged end portions of the other of the beams; two layers of elongated boards superimposed upon said quadrangular corner portion and constituting a web covering said quadrangular corner portion and being continuous with the web of one of said beams, the boards of one of said layers extending substantially parallel to one diagonal of said quadrangular corner portion and the boards of the other of said layers extending substantially parallel to the other diagonal of said quadrangular corner portion; and a plurality of connecting means firmly connecting said superimposed layers of elongated boards to each other and to said flanged end portions and said laths at a substantial number of points spaced in longitudinal direction of said flanged end portions all along the same whereby components of stress created at any of said spaced points are directed in direction of, and taken up, by a board parallelogram having a vertex in the stressed point and being composed of one pair of boards of each of said layers.

7. A beam structure comprising two angularly arranged flanged beams having flanges along the edges thereof, flanged end portions at the ends of said beams to be joined at a corner, said flanged end portions of one beam overlapping said flanged end portions of the other beam and forming with the same a quadrangular corner

portion, said flanged end portions at the ends of one of the beams being substantially parallel and horizontal, said flanged end portions at the ends of the other of the beams being substantially upright; a pair of strengthening laths being arranged between said flanged end portions of one of the beams and parallel to said flanged end portions of the other of the beams; two layers of elongated boards superimposed upon said quadrangular corner portion and constituting a web covering said quadrangular corner portion and being continuous with the web of one of said beams, the boards of one of said layers extending substantially parallel to one diagonal of said quadrangular corner portion and the boards of the other of said layers extending substantially parallel to the other diagonal of said quadrangular corner portion; and a plurality of nails firmly connecting said superimposed layers of elongated boards to each other and to said flanged end portions and said laths at a substantial number of points spaced in longitudinal direction of said flanged end portions all along the same whereby components of stress created at any of said spaced points are directed in direction of, and taken up, by a board parallelogram having a vertex in the stressed point and being composed of one pair of boards of each of said layers.
